OFFSET PRINTING MACHINE AND SHEET GAGE

Luis Mestre, New York, N.Y., assignor to Lewfor Development Corporation, New York, N.Y., a corporation of New York

Original application September 2, 1953, Serial No. 378,035, now Patent No. 2,821,911, dated February 4, 1958. Divided and this application May 16, 1957, Serial No. 659,595

8 Claims. (Cl. 271—53)

The present invention relates to offset printing machines and the principal object of the invention is to provide a gage or stop means embodying novel and advantageous features of construction and capable of producing novel and advantageous results. Printing machines of this character comprise a plate cylinder, a blanket cylinder, and an impression cylinder and may include a delivery cylinder. The gage or stop means is located at or adjacent to the impression cylinder to stop the sheet and control the position of the leading edge of the sheet at the cylinder.

An object of the invention is to provide a machine of the type specified embodying novel and advantageous means for gaging or stopping and aligning sheets of material such, for example, as a sheet of paper for engagement by grippers on the impression cylinder.

Another object of the invention is to provide a stop gage with new and novel adjusting means.

This application is a division of application S.N. 378,035 filed September 2, 1953, now Patent 2,821,911 dated February 4, 1958.

Further objects, features and advantages will appear upon consideration of the following detailed description and of the drawings, in which:

Fig. 1 is a sectional view through an impression cylinder taken on line 1—1 of Fig. 2; giving an elevational view of the gage or stop means.

Fig. 2 is a partial end view of the impression cylinder and the gage or stop means.

Fig. 3 is a vertical section through the impression cylinder and the gage or stop means taken on line 3—3 of Fig. 1, the impression cylinder being in position for means carried thereby to grip the leading edge of a sheet of paper fed thereto;

Fig. 4 is a detail end view of a cam follower for the gage adjustment as taken on line 4—4 of Fig. 1.

Fig. 5 is a side view of the cam follower as viewed on line 5 of Fig. 2.

Fig. 6 is a cross section through a rockshaft for the gage adjustment taken on line 6—6 of Fig. 1.

The frame of the machine comprises spaced front and rear frame members or plates 40 and 41 respectively, connected by cross pieces, (not shown). The cylinders and gage parts are mounted upon the frame members. Each sheet of paper P is picked from a pile or stack (not shown) and advanced to the impression cylinder 66 of the offset printing machine by suitable feeding mechanism (not shown). The impression cylinder is rotatably mounted on a shaft 49 and driven by a gear 50. A blanket cylinder 48 carries the ink for making an impression on the sheet as it passes between the impression cylinder and the blanket cylinder.

2

The sheet P from the feeding mechanism passes over a lower supporting plate 57 and beneath an upper guide plate 58 to a position where it is stopped by engagement of its leading edge with substantially vertical stop fingers 59 or teeth 59 of a gage member or comb 60 forming a part of the gage or stop. The lower ends of the stop fingers 59 are normally housed in slots 62 in the end edge of the plate 58 which extends beyond the edge of plate 57. In the position illustrated the stop fingers project below the lower face of plate 58 into the path of each sheet P. The comb or gage member 60 has a flat top 63 adjustably mounted on the top of a rockshaft 64 and provided at its forward edge with the fingers 59 which project downwardly at substantially right angles to the top. The stop fingers 59 occupy alternate slots 62 in plate 58 leaving the remaining slots 62 available for the passage of spring grippers or gripper fingers 65 carried by an impression cylinder 66 having ends 66a. As shown in Fig. 1, the stop fingers 59 are separated by high arched openings 10 to accommodate or permit the sheet grippers or gripper fingers 65 to pass therebetween.

Fixed to the impression cylinder 66 is a cam 67 having an outer edge or high portion in the shape of a circle except for a low portion 68 (Fig. 2). The cam 67 engages a follower 69 on an arm 70 adjustably mounted on the rockshaft 64 and moves the stop fingers or teeth 59 of said stop 60 to raised position after a sheet P has been clamped by the grippers 65 of impression cylinder 66 and holds the stop raised until just prior to 20 another sheet approaching stop position. The follower 69 then drops into the lower part 68 of the cam and pivots the stop fingers 59 into sheet stopping position for engagement of the leading edge of the sheet with the stop fingers until gripped by gripper fingers 65 of the impression cylinder 66. The follower 69 is pressed against cam 67 by a spring 51 having one end connected with an arm 52 secured to the rockshaft 64 and the other end attached to a fixed pin 53 carried by a frame plate (Fig. 5).

40 A feature of the invention relates to novel and advantageous means for adjustably mounting the gage or particularly the comb 60 on the rockshaft 64. This means comprises a pivot in the form of a screw 71 passing through an opening in top 63 of the comb substantially midway between the ends thereof and threaded into the rockshaft 64. One end of the comb 60 is urged forwardly by a helical compression spring 72 having one end mounted in a bore 73 in the shaft and the other end in engagement with the rear or inner face of the comb 60. Obviously the pressure of spring 72 on the end of the comb will urge the other end of comb rearwardly about the pivot formed by the screw 71.

The actual adjustment of alignment of the comb or gage member 60 is effected by means of a nut 74 threaded on the rockshaft 64 and having a tapered or conical end engaging a finger 75 projecting from the adjacent end of said comb 60 for engagement by the tapered end of the nut 74. By screwing the nut 74 towards the pivot 71, the end of the stop, gage or comb 60 at the nut 74 will be moved away from the rockshaft 64 in the direction of travel of the sheets and the other end of said stop or comb at the spring will be swung about the pivot 71 towards the rockshaft and against resistance of said spring 72. By movement of nut 74 in the proper direction the comb 60 may be adjusted to provide proper alignment of

the gage for the leading edge of the sheets P as the sheets are fed to the impression cylinder 66.

Another feature of the invention relates to regulation of the movement of the stop or comb 60 about the axis of rockshaft 64 by adjusting the position of arm 70 around said rockshaft, thereby regulating the forward or rearward position of the stop 60 and of the ends of stop fingers or teeth 59. As illustrated in Figs. 4 and 5, arm 70 is flat and has a hub 76 at its inner end mounted on the rockshaft 64 and fixed to a collar 77 rotatably mounted on the same rockshaft. At one side of hub 76 is a projection 78 having at its lower edge an ear 79 at right angles thereto and having a screw-threaded opening therein.

Adjacent to hub 76 is a hub 80 mounted on rockshaft 64 and secured to a collar 81 which is fixed on rockshaft 64 by a screw 85. The hub 80 has an ear 82 projecting laterally over ear 79 and having an opening therethrough to receive a bolt of screw 83. The screw 83 is inserted through the opening in ear 82, through a helical spring 84, and is screwed into the screw-threaded opening in ear 79. The helical spring 84 urges ears 79 and 82 apart to the distance permitted by screw 83. The adjustment of the arm 70 with reference to rockshaft 64 may be varied within suitable limits of adjustment by turning screw 83 to the required position and thereby adjusting the position of the stop fingers on teeth 59 forwardly or rearwardly of the travel of the sheet or relatively to the impression cylinder.

The surface of the impression cylinder 66 is cylindrical except for a longitudinal channel or trough 90 having a peripheral opening to accommodate the gripper fingers 65 and a shaft 91 on which they are pivotally mounted. The shaft 91 is mounted in the ends 66a of impression cylinder 66. As shown on Fig. 1, fingers 65 are spaced to pass through slots 92 in a cover 93 for said channel 90. Other slots 89 in the cover receiving the fingers 59 of stop 60 at the time the stop is lowered or pivoted to stop position. Suitable operating means 87 are provided to open and close the gripper fingers 65 in timed relation with the rotation of the impression cylinder. A suitable means is shown in the aforesaid parent patent.

This invention is presented to fill a need for improvements in Offset Printing Machine and Sheet Gage. It is understood that various modifications in structure, as well as changes in mode of operation, assembly and manner of use, may and often do occur to those skilled in the art, especially after benefitting from the teachings of an invention. Hence it will be understood that this disclosure is illustrative of preferred means of embodying the invention in useful form by explaining the construction, operation and advantages thereof.

What is claimed is:

1. In a machine of the class specified to make impressions on successive sheets, the combination of a frame, a cylinder mounted for rotation in the frame and having a longitudinal opening, means at said opening to grip the leading edge of a sheet presented at said opening at a predetermined point in the rotation of said cylinder, and a single gaging member of a substantial length for the leading edge of each sheet mounted on the frame adjacent to the cylinder, means to move the gaging member into and away from the path of movement of a sheet to the cylinder, comprising means for adjusting said gaging member in accordance with the transverse direction of the leading edge of a sheet.

2. In a machine of the class specified to make impressions on successive sheets, the combination of a frame, a cylinder mounted for rotation in the frame and having a longitudinal opening, means at said opening to grip the leading edge of a sheet presented at said opening at a predetermined point in the rotation of said cylinder, and gaging means for the leading edge of each sheet mounted on the frame adjacent to the cylinder, means to move the gaging means into and away from the path of

movement of a sheet to the cylinder, comprising means for adjusting the relative position of the gaging means with respect to the cylinder.

3. In a machine of the class specified to make impressions on successive sheets, the combination of a frame, a cylinder mounted for rotation in the frame and having a longitudinal opening, means at said opening to grip the leading edge of a sheet presented at said opening at a predetermined point in the rotation of said cylinder, and gaging means for the leading edge of each sheet mounted adjacent to the cylinder comprising a transverse shaft mounted on the frame, a gage member having a top resting on said shaft and pivoted centrally thereon and fingers projecting downwardly to engage the leading edge of said sheet, and means to rock the shaft to move the fingers into and away from the path of movement of a sheet to the cylinder.

4. In a machine of the class specified to make impressions on successive sheets, the combination of a frame, a cylinder mounted for rotation in the frame and having a longitudinal opening, means at the opening to grip the leading edge of a sheet presented at said opening at a predetermined point in the rotation of said cylinder, and gaging means for the leading edge of each sheet mounted adjacent to the cylinder comprising a transverse shaft mounted on the frame, a gage member having a top resting on the shaft and pivoted centrally thereon and fingers projecting downwardly to engage the leading edge of a sheet, and means to rock the shaft to move the fingers into and away from the path of movement of a sheet to the cylinder, means for urging one end of said gage to swing it about its pivot, and positive means for swinging the gage against such urging means.

5. In a machine of the class specified to make impressions on successive sheets, the combination of a frame, a cylinder mounted for rotation in the frame and having a longitudinal opening, means at said opening to grip the leading edge of a sheet presented at said opening at a predetermined point in the rotation of said cylinder, and gaging means for the leading edge of each sheet mounted adjacent to the cylinder comprising a transverse rockshaft mounted on the frame, aligned stop fingers carried by said rockshaft, and means for raising and lowering said stop fingers comprising an arm connected at one end to the shaft, a cam on the cylinder engaged by the arm and which cam has a low and high portion to move the stop fingers into and away from the path of feed of a sheet to the cylinder.

6. In a machine of the class specified, the combination of a cylinder having means to grip the leading edge of a sheet supplied thereto, and means for gaging the forward edge of each sheet preparatory to the action of said gripping means and mounted adjacent to the cylinder comprising a rockshaft, gaging fingers extending downwardly at the forward side of said rockshaft, a cam mounted on said cylinder, an arm mounted at its inner end on said rockshaft, a follower at the other end of the arm to engage said cam, a screw and means controlled by the screw to adjust the position of the arm with reference to the rockshaft and hold such adjustment.

7. In a machine of the class specified, the combination of a cylinder having means to grip the leading edge of a sheet supplied thereto, and means for gaging the forward edge of each sheet preparatory to the action of said gripping means and mounted adjacent to the cylinder comprising a rockshaft, gaging fingers extending downwardly at the forward side of the rockshaft, a cam mounted on the cylinder, an arm mounted at its inner end on said rockshaft, a follower at the other end of the arm to engage said cam, a member fixed on the shaft adjacent said arm, a helical compression spring interposed between the member and the arm to change their relative positions around the shaft, means for compressing the spring comprising a rod extending through the spring and threaded at one end, and a nut on the threaded end.

8. In a machine of the class specified, the combination of a cylinder with gripping means to grasp the leading edge of a sheet fed thereto, a gaging means comprising a shaft, a stop comprising a top overlying said shaft, a vertical pivot projecting from the top of the shaft through the central part of the top, a comb projecting from said top downwardly at the front of the shaft and having a plurality of fingers, a helical spring having one end in a corresponding bore in the shaft spaced from the vertical pivot and engaging the inner surface of one end of the 10 comb, and a conical nut threaded on the shaft at the other

end of the comb to force the adjacent end of the comb away from the shaft against the action of the spring, and means to rock the shaft including an arm on the shaft and a cam on the cylinder engaging the arm.
